Primary Examiner — Messina L Smith*Assistant Examiner* — Kwabena A. Ankobiah(74) *Attorney, Agent, or Firm* — CHRISTENSEN O'CONNOR JOHNSON KINDNESS PLLC(57) **CLAIM**

The ornamental design for a coordinate input device, as shown and described.

DESCRIPTION

FIG. 1 is a front, bottom and left perspective view of a coordinate input device according to my new design;
FIG. 2 is a rear, top and left perspective view thereof;
FIG. 3 is a front elevational view thereof;
FIG. 4 is a rear elevational view thereof;
FIG. 5 is a left side elevational view thereof, wherein the right side elevational view is a mirror image thereof;
FIG. 6 is a top plan view thereof;
FIG. 7 is a bottom plan view thereof; and,
FIG. 8 is an enlarged rear, top and left side perspective view thereof, taken from encircled portion 8 in FIG. 2.
The broken lines in the drawings represent portions of the coordinate input device and form no part of the claimed design. The dot-dot dash broken lines in FIGS. 2 and 8 are included to show a partially enlarged view only and form no part of the claimed design.
